(57) **CLAIM**

The ornamental design for a light emitting diode, as shown and described.

DESCRIPTION

FIG. 1 is a top perspective view of a light emitting diode showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a cross-sectional view taken along line 9-9 of FIG. 5;

FIG. 10 is a cross-sectional view taken along line 10-10 of FIG. 5; and,

FIG. 11 is a cross-sectional view taken along line 11-11 of FIG. 5.

The broken lines illustrate portions of the light emitting diode which form no part of the claimed design. The oblique line shading represents transparency.
